UNITED STATES PATENT OFFICE.

ANTOINE VERICEL, OF BALDWIN, NEW YORK, ASSIGNOR TO DOEHLER DIE-CASTING CO., A CORPORATION OF NEW YORK.

DESIGN FOR A PAN OR THE LIKE.

Application filed May 23, 1928. Serial No. 26,825. Term of patent 3½ years.

To all whom it may concern:

Be it known that I, ANTOINE VERICEL, a citizen of the Republic of France and a resident of Baldwin, in the county of Nassau and State of New York, have invented a new, original, and ornamental Design for Pan or the Like, of which the following is a specification, reference being had to the accompanying drawings, forming part thereof.

Figure 1 is a side view of a pan showing my new design, and

Figure 2 is a sectional view taken on the line 2—2 of Figure 1.

I claim:

The ornamental design for a pan or the like as shown.

ANTOINE VERICEL.
